CLAIM

The ornamental design for a tile connector for animal communications, as shown and described.

DESCRIPTION

FIG. 1 is a perspective view of a tile connector for animal communications according to the design.

FIG. 2 is a top view of the tile connector for animal communications of FIG. 1.

FIG. 3 is a bottom view of the tile connector for animal communications of FIG. 1.

FIG. 4 is a front elevation view of the tile connector for animal communications of FIG. 1.

FIG. 5 is a left elevation view of the tile connector for animal communications of FIG. 1.

FIG. 6 is a rear elevation view of the tile connector for animal communications of FIG. 1; and,

FIG. 7 is a right side elevation view of the tile connector for animal communications of FIG. 1.

The dashed dot dashed broken lines illustrate the bounds of the claim and the dashed broken lines illustrate portions of the tile connector for animal communications. The broken lines form no part of the claimed design.

1 Claim, 2 Drawing Sheets
